CLAIM

The ornamental design for a removable paint can rim, as shown and described.

DESCRIPTION

FIG. 1 is a perspective view of the paint can rim as seen from above;

FIG. 2 is a top elevational view thereof;

FIG. 3 is a side elevational view thereof as seen from the bottom of FIG. 2, the other side being a mirror image thereof; and,

FIG. 4 is a cross section taken generally along line 4—4 of FIG. 2.

The broken line showing of paint can and lid is included for the purpose of illustrating and forms no part of the claimed design.
